Primary Examiner — Jae Liang*Assistant Examiner* — Bryan C Gusman(74) *Attorney, Agent, or Firm* — JEEN IP LAW, LLC(57) **CLAIM**

The ornamental design for a lift table, as shown and described.

DESCRIPTION

FIG. 1 is a rear, left and top perspective view of a lift table, showing my new design;

FIG. 2 is a front, right and bottom perspective view thereof;

FIG. 3 is a front view thereof;

FIG. 4 is a rear view thereof;

FIG. 5 is a right side view thereof;

FIG. 6 is a left side view thereof;

FIG. 7 is a top plan view thereof;

FIG. 8 is a bottom plan view thereof;

FIG. 9 is an enlarged view of portion of FIG. 1 thereof;

FIG. 10 is an enlarged view of portion of FIG. 1 thereof;

FIG. 11 is an enlarged view of portion of FIG. 1 thereof;

FIG. 12 is an enlarged view of portion of FIG. 2 thereof; and,

FIG. 13 is an enlarged view of portion of FIG. 2 thereof.

The broken lines shown in the drawings illustrate portions of the lift table that form no part of the claimed design.
